Primary Examiner — Lucy Lieberman(74) *Attorney, Agent, or Firm* — Krieg DeVault LLP;
Clifford W. Browning(57) **CLAIM**

The ornamental design for a watch dial, as shown and described.

DESCRIPTION

FIG. 1 is a top view of the watch dial of the present invention. FIG. 2 is a bottom view of the watch dial of FIG. 1. FIG. 3 is a right side view of the watch dial of FIG. 1, the left side view being a mirror image thereof; and, FIG. 4 is a top, right-side perspective view of the watch dial of FIG. 1.
